UNITED STATES PATENT OFFICE.

GASTON ALBERT DURET, OF PARIS, FRANCE.

PROCESS FOR UTILIZING THE WATER FROM PULP PRESSES AND THE RESIDUAL WATER PRODUCED BY THE EXTRACTION OF THE JUICES IN THE BEETROOT-SUGAR INDUSTRY.

No Drawing.

Application filed March 31, 1921. Serial No. 457,566.

To all whom it may concern:

Be it known that I, GASTON ALBERT DURET, a citizen of the French Republic, and resident of Paris, France, have invented 5 a new and useful Process for Utilizing the Water from Pulp Presses and the Residual Water Produced by the Extraction of the Juices in the Beetroot-Sugar Industry, of which the following is a specification.

10 This invention has for its object the concentration of the water from pulp presses and residual water produced by the extraction of the juices in the beetroot sugar industry, for the purpose of utilizing all the 15 food or fertilizing matters they contain.

The average analysis of the water from pulp presses per litre is the following:

Sugar, 4 gr. 6 to 5 gr.; total nitrogen, 0 gr. 21 to 0 gr. 26; ashes, 0 gr. 90 to 1 gr. 30; 20 organic matters, 6 gr. to 8 gr.; matters in suspension, 5 gr. to 22 gr.

Up to this day these waters were disposed of either by distributing them in the ground or by filtration or by bacterian sowings so 25 as to destroy any fermentation, in order to allow this water to return to the rivers.

None of these processes has given entire satisfaction and their application was in most cases very costly.

30 This invention consists: in concentrating these waters by subjecting them to an evaporation in multiple-effect apparatus, working under pressure so as to be able to replace the quantity of high pressure steam entering in the apparatus, by an equal quantity 35 of steam but of lower pressure, which can be used in the works instead of the initial steam; in mixing the syrup or liquor obtained with chopped straw, oil-cakes or any other ligneous or woody substances, to produce a food of great value for cattle; the syrup may also, owing to the fertilizing elements it contains, be used for the manufacture of manure.

40 For the application of this process, various cases may occur:

1st case.—Case of a central sugar mill where all the beetroot juices are evaporated and converted into sugar.

50 *2nd case.*—Case of a rasping mill where the extraction of the juice is simply effected and subsequently sent to the central mill.

1st case.—Central mill: The initial steam considered comes from generators and its

pressure may reach ten to twelve kilograms. 55 In the usual conditions of working, this steam would be sent in the evaporating apparatus for the sweet juice of the mill under a maximum pressure of 1 kg. 500 to 2 kg. There is therefore an unnecessary expansion 60 of this steam without work between 12 kg. and 2 kg.

In the process forming the subject matter of this invention, this steam is sent in the evaporating apparatus for water from pulp 65 presses, constituted by 2, 3 or 4 effects.

The direct steam will first enter the evaporating apparatus for water from pulp presses at 6 kg. for instance and the last evaporator of this apparatus allows the 70 escape, under the form of steam evolved from the water from the pulp presses; the same quantity of steam at 2 kg. and this quantity of steam will be used in the evaporating apparatus for the sweet juices of 75 the mill instead of the live steam.

It is preferable not to subject the water from pulp presses to a temperature higher than 140° C., so as to avoid the formation of caramel and of nondigestible albumin. 80

The water from pulp presses will thus be concentrated up to 35°—38° Baumé for obtaining a liquor containing all the substances contained in the initial water and it is this liquor which will, when mixed with 85 chopped straw, oil-cakes or any other ligneous or woody substances, constitute a food of great value for cattle. This liquor may also, as above stated enter in the composition of manure. 90

2nd case.—Rasping mill: The steam considered is that issuing from the steam engine of the rasping mill with the necessary addition of direct steam permitting to effect the heating of the apparatus for extracting 95 the beetroot juice.

Usually the steam issues from the steam engine at 0 kg. 500 and this steam, to which is added or not live steam, is used for the heating of the diffusion battery. 100

In the process forming the subject matter of this invention, the steam is caused to issue from the steam engine at 3 kg. and this steam and the necessary direct steam are sent in an apparatus for the evaporation of water from pulp presses operating under pressure and with multiple effect. The last chest of evaporating apparatus will 105

send, for heating the diffusion battery, a weight of steam equal to that entering in the evaporating apparatus and at a pressure of 0 kg. 100 to 0 kg. 150. The liquor obtained must weigh, as previously indicated, 5 35 to 38° Bé. in order to be subjected to the same uses.

In both the cases considered, it will be noted that the concentration of the water from pulp presses is thus effected without supplementary consumption of steam, since it is the same quantity of steam which may be disposed of that is first used at a higher pressure for causing it to drop in a useful manner instead of causing it to expand without doing any work.

On the other hand it is also to be noted that the apparatus works under pressure at a temperature higher than 105° C. This 20 temperature is necessary for ensuring the conversion of the insoluble pectic substances

into soluble metapetic substances, in order to avoid the fouling of the tubes of the evaporating apparatus. The albuminoid substances alone will be coagulated by the 25 heat, but they will remain digestible if they are not subjected to a temperature higher than 140° C.

Use must be made of an evaporating apparatus ensuring an intense circulation of 30 the liquid.

Claim:

Process for the utilization of the residual waters of the pressing of the pulp beetroot and of the residual waters of the extraction 35 of the juice in the manufacture of sugar, which comprises evaporating said waters to a syrupy consistency at a temperature between 105° and 140° C.

In testimony whereof I have signed my 40 name to this specification.

GASTON ALBERT DURET.
